UNITED STATES PATENT OFFICE.

JOHN O. TAYLOR, OF OAK PARK, AND HARRY DOYLE, OF NAPERVILLE, ILLINOIS, ASSIGNORS TO KROEHLER MANUFACTURING COMPANY, OF NAPERVILLE, ILLINOIS, A CORPORATION OF ILLINOIS.

CUSHION-STUFFING MACHINE.

Application filed December 13, 1926. Serial No. 154,336.

This invention relates to a machine for stuffing cushions or mattresses for beds, davenports and the like, and the principal object is to provide a machine of this class which will satisfactorily fill a cushion cover of considerable length, such for example as a full length day bed.

Other objects are to provide stuffing means insertable within and withdrawable from a full length cushion; to provide a raisable cover and a lock therefor, and to engage the cover for raising certain of the cushion stuffing means and to automatically limit the movement of the cushion stuffing means to one complete operation; to prevent the filling of a cushion from being withdrawn; to provide adjustable means for varying the width of the cushions to be filled, to provide rotating means for controlling the movement of the cushion cover; and in general to produce the construction herein shown and described.

In the accompanying drawings:

Figure 1 is a side elevation of a machine constructed in accordance with the principles of this invention;

Figure 2 is a section taken on the line 2-2 of Figure 5;

Figure 3 is a section taken on the line 3-3 of Figure 5;

Figure 4 is a view of the discharge end;

Figure 5 is a broken section taken on the line 5-5 of Figure 2 with the plunger in one position;

Figure 6 is a similar section showing the plunger in another position;

Figure 7 is an end view of the driving mechanism; and

Figure 8 is a detail of the rotating means at the discharge end of the machine.

In filling cushions of considerable length, great difficulty is encountered in evenly distributing the filling or stuffing, for if a simple plunger is used to force the filling into the cushion cover, the filling is likely to wad up in a bunch, or to leave a space within the cover, which is not sufficiently filled. In order to overcome these difficulties, the present invention includes the use of a number of thin strips which form a partially open bottom and top between which the filling is placed in the proper position, and by which the filling is partially compressed so that the filling can be carried

or projected in a thin pad or layer between the strips to fill a cushion cover of considerable length, as compared with its width and thickness. The thin strips are then withdrawn and the filling prevented from following the strips in their withdrawing movement.

In carrying out this invention, a suitable frame work designated generally with the reference numeral 1 is provided, which has an operating bed at a convenient height consisting of a number of slats or strips 2 extending lengthwise of the frame and spaced apart to provide runways for operating chains 3 and for a direction control member 4. Pivoted at one end of the frame is a cover 5 raised or counterweighted by a rope 6 attached to the free end and locked in its lower position by means of a rod 7 which extends loosely through a bracket 8 on the cover 5, one end being engageable in a plate 9 attached to the frame and the other end being engageable under a hook member 10 carried by the cover. As the rod is flexible, it can be engaged in the plate 9 and then sprung under the hook member 10.

At the hinged end of the cover 5 is an electric driving motor 11 mounted in the frame and connected through a reduction mechanism 12 to a cross shaft 13, upon which are gears 14 for driving the stuffing plunger. A reversing switch controller 15 for driving the motor 11 has a contact arm 16 with projections 17 and 18 thereon, adapted to be engaged by a finger 19 depending from the controlling member 4 which is slidable between the slats 2 and has projections 20 and 21 at the ends. The movement of this controlling member 4 causes the finger 19 to engage the projections 17 or 18, causing the motor to be reversed in its direction of movement or to be stopped.

The plunger mechanism comprises a head comprising cross pieces 22 for each plunger to which the chains 3 are attached for positively moving the plungers in both directions. A member 23 is attached to the under side of one of the plunger heads 22 which has a downward projection 24 disposed between the slats 2 in position to engage the upward projections 20 and 21 of the operating member 4 so that the movement of the

plunger head in one direction causes the engagement of this projection 24 to move the operating member 4 in one direction or thereby reversing or stopping the motor. 5 This operation occurs at or near the end of travel of the plunger.

Attached to each plunger head 22 are a number of thin strips 25 which are spaced apart, resting upon the slats 2 so that the 10 filling material 26 can be properly positioned thereon when the cover 5 is raised, as indicated in the broken outline in Figure 1. Corresponding thin strips 27 are connected by hinges 28 to each plunger head 22 15 so that these upper strips can be raised for arranging the stuffing or filling upon the bed of the machine. In order to raise the upper strips 27 simultaneously with the cover 5, a cross piece 29 is disposed beneath 20 the strips and hook members 30 are attached to the under side of the cover 5, adapted to engage beneath the cross member 29 so that when the cover is raised, the upper strips 27 will also be raised as indicated in Figure 1. 25 This will allow free access to the bed of the machine for adjusting and placing the filling on the lower strips 25. When the plunger heads 22 are advanced, the cross pieces 29 slip out of engagement from the 30 hooks 30 so that the covers 5 may be raised without raising the strips 27. The present machine is shown as a double pad filler with two covers, as shown more clearly in Figure 2, with a central dividing partition 31 and 35 with adjustable side pieces 32 for limiting the width of the cushions to be made. These side pieces are adjustable inwardly by means of slotted brackets 33 having wing nuts 34 operating in the slots and connected to the frame of the machine for adjusting and holding the side pieces 32 with respect thereto.

At the discharging end of the machine are adjustable sleeves over which cushion covers 45 35 are applied, which are to be filled. These sleeves each comprise an inner member 36 and an outer slidable member 37 movable inwardly toward the other sleeve member on the guides 38 so that the width of the cushion 50 can be varied. The movable section of the sleeve is adjustable and is held in place by a slotted bracket 33 and a wing nut 34 (not shown) similar to that shown in connection with the side rail 32. In the present machine, the two sleeve members 36 are placed close together as shown more clearly in Figure 3 so that a pair of pads to be filled 55 may have covers 35 which are secured together, as by stitching 39 so that they are foldable one upon the other.

A rotating device is provided at the discharging end to prevent the cushion cover from slipping too readily from the sleeve on which they are threaded, and this rotating 60 device comprises side supports 40 at-

tached to the machine frame to each of which a pair of levers 41 and 42 are pivoted, the former intermediate its ends and the latter at the end thereof. The corresponding levers on the opposite sides are connected by cross pieces 43 and 44 (see Figure 4), each having one or more pads 45 of yielding material such as felt or the like to engage the opposite faces of the cushion cover at the ends of the sleeves. These 75 levers of each pair are connected by a link 46 which has a fixed pivotal connection with the lower lever 41 and a slot 47 and pin 48 connected with the upper lever 42. Each link 46 is connected between the pivot and the contacting end of the upper lever and outside of the space between the pivot and contacting end of the lower lever, and a spring 49 is connected to the free end of the lower lever so that the movement of the 80 upper lever 42 causes a corresponding movement of the lower lever, and the same spring not only applies the rotating means to the upper and lower sides of the cushion covers but also when the upper levers are resting, 85 as shown in Figure 8, the spring holds the levers in their open position.

Although the filling strips 25 and 27 are thin and smooth and the extremities 50 are rounded to prevent frictional engagement with the covers and also with the filling material itself, the compression of the strips may tend to withdraw the filling material from the cushion after the cushion is formed. In order to overcome any such 100 tendency, the upper cross piece 44 of the retarding device is provided with a number of hinged fingers 51 which extend downwardly over the ends of the sleeves, but rotate freely upward when a cushion is being 105 filled, as indicated in Figure 6, but which as soon as the cushion cover and the filling have been projected beyond the end of the sleeve will turn downwardly in the path of the filling so that if there is any tendency 110 of the filling or cover to follow the strips 25 and 27 upon their withdrawing movement, the fingers 51 will engage them and prevent them.

In operation, the cover or covers 5 and 115 the upper filling strips 27 are raised as indicated in Figure 1; the filling is then applied upon the bed of the machine over the strips 25 and beyond the extremities of the strips, as shown in Figure 5; the retarding device is raised, as shown in Figure 8 to allow the cushion cover to be fitted on the sleeve, the cover is then closed and held in position by the locking rod 7 and the retarding device is rotated to the retarding 120 position as shown in Figure 1. A table or bench 52 is usually disposed in front of the machine, substantially at the height of the discharging sleeves so that as the plungers project the filling into the cushion cover, 125

it all will rest upon the table 52 and will slide freely upon it for the full length of the cushion to be made. To operate the projecting mechanism an electrical connection is closed for the motor 11, which moves the plunger head 22 in a discharging direction until the projection 24 engages the upward extension or projection 21 of the operating member 4, which moves the finger 19 into engagement with the projection 18 of the controller 15, which thereupon assumes the position shown in Figure 6, reversing the direction of rotation of the motor and thereby withdrawing the plunger and its filling strips from the filled cushion cover. This withdrawing action continues until the contact 24 engages the other end 20 of the control member 4 which causes the movement thereof so that the finger 19 engages the projection 17 of the controller, returning it to the position shown in Figure 5 and shutting off the motor. Thus a complete set of operations has been completed and the machine is ready for another similar action and use.

We claim:

1. In a cushion stuffing machine, a fixed bed or frame, a plunger slidable thereon having two sets of strips one of which is hinged to the plunger, and a cover movable upwardly from the frame and having means for engagement with the hinged set of strips for moving the latter upwardly with the cover.
2. In a cushion stuffing machine, means forming a horizontal bed, a cover applicable over the bed, a plunger reciprocable upon the bed below the cover and comprising upper and lower sets of strips, the upper strips being hinged at one end to the plunger, and means in connection with the upper set of strips and the cover for raising the strips when the cover is raised.
3. In a cushion stuffing machine, a frame forming a horizontal bed, a cover hinged at one end of the bed, a reciprocable plunger movable upon the bed below the cover and comprising two sets of strips adapted to extend above and below a cushion stuffing placed therebetween, means for confining the strips in discharging the filling, and means for locking the free end of the cover in engagement with the frame during the reciprocating movement of the plunger, said means including a cross piece with an apertured plate and a flexible rod engaging the cover and insertable in the aperture of the plate.
4. In a cushion stuffing machine, a plunger having a plurality of hinged strips, a hinged

cover movable downwardly over the plunger and its hinged strips, a hook member extending between and below the hinged strips, and a cross piece engaged by the hook member so that the hinged strips may be reversed with the cover.

5. A cushion stuffing machine, comprising a pair of reciprocable plungers, a partition separating the plungers, a pair of sleeves arranged close together through which the plungers move, the sleeves being placed close together so that a double cushion cover can be placed thereon and the two portions thereof filled simultaneously, such cushion being foldable upon itself and the division line therebetween.

6. A sectional cushion stuffing machine, comprising cushion cover receiving sleeves placed close together, a cushion filling bed, partition means in the bed dividing it into compartments in accordance with the sleeves, and separate plungers simultaneously operated for separately ejecting cushion fillings through the sleeves from the bed plate and into a cushion cover which is connected between the sleeves.

7. In a sectional cushion stuffing machine, in accordance with claim 6, a pair of cushion cover receiving sleeves, each comprising two substantially U-shaped sections slidable laterally one within the other, the adjacent inner sleeves being spaced apart slightly so that the cushion partition can be inserted therebetween, and the two outer slidable sections being adjustable laterally to vary the width of the cushion to be formed, and adjusting means for holding these outer sections in place.

8. In a cushion stuffing machine, a sleeve for receiving a cushion cover to be filled, means for projecting a filling through the sleeve, hinged levers having means carried thereby for engaging a cover at the upper and lower front edges of the sleeve for retarding the movement of the cover therefrom, a link connecting the levers for movement together, and a single spring connected to one of the levers for holding them both yieldingly in open and closed position.

9. In a cushion stuffing machine, a sleeve for receiving a cushion cover to be filled, means for projecting a filling through the sleeve and into a cushion cover, and means yieldingly engaging a cushion cover during its filling movement to prevent the return movement of a filling and a cover with the returning movement of the said projecting means.
